APPARATUS FOR HANDLING MIXTURES OF SOLID MATERIALS

John P. Hubbell, Garden City, N.Y., assignor to the United States of America as represented by the United States Atomic Energy Commission

Application June 7, 1951; Serial No. 230,308

17 Claims. (Cl. 141—73)

This invention relates generally to a new and improved apparatus for handling a mixture of finely subdivided materials requiring a compacting action thereon although in its broader aspects it comprehends the handling of a single material. In the processing of various solid materials which may have components of differing specific gravities and which may at times be so finely subdivided as to form a dust hazard, it has been found that conventional dispensing and filling apparatus does not provide a complete solution to the problems encountered. For example, when filling a container with a mixture of two finely divided materials which must be uniformly dispersed in preparation for subsequent processing, which may be toxic or radioactive in character, and which also must be compacted to give a body of appreciable density, it is evident that special equipment is required since a conventional dispensing and filling structure is inadequate for these purposes.

The invention therefore has as an object the provision of a new and improved apparatus for filling containers with a substantially uniformly dispersed mixture of solid materials.

A second object is to provide a new and improved apparatus for compacting a mixture of solid materials within a container.

A third object is to provide a new and improved apparatus for preventing escape of dust during the filling of a container with finely subdivided materials.

A further object is to provide a filling and compacting apparatus which may be operated by remote control.

Another object is to provide a new and improved combination of filling apparatus and automatically retractable means for supporting a container to be filled.

Still another object is to provide an apparatus for filling containers lined with a fragile material and for compacting a mixture of materials interiorly of said lined container.

Other objects and advantages will become apparent as the description proceeds when considered in conjunction with the accompanying drawings in which

Figure 1 is an assembly view showing one arrangement of apparatus capable of carrying out the invention, and with the apparatus being foreshortened in certain portions to depict a preferred combination of structure in a single figure.

Figure 2 is a sectional view to an enlarged scale showing the relationship of the container to be filled and the filling and compacting means at the beginning of a filling operation.

Figure 3 is a sectional view to an enlarged scale showing the relationship of the filled container and the filling and compacting means at the conclusion of the filling operation.

Figure 4 is a view partly in section of the upper portion of the filling means; and

Figure 5 is a sectional view taken along line 5—5 of Figure 3 and on a larger scale.

Although the invention will be useful in the handling

2

and packaging of diverse solid materials it is especially useful in the handling of mixtures of finely divided solids preparatory to a chemical reducing process carried out in a crucible or "bomb" container. For example, in one method of producing uranium metal a mixture of finely divided uranium fluoride salt and finely divided magnesium is heated in a metal crucible having a uniformly thick dolomite lining therein. In general, the more compactly such mixture is packed into the crucible, the more efficiently the process may be conducted with a given amount of time, heat and labor. However, precautions must be taken to avoid the escape of the radioactive uranium dust and to avoid any damage to the relatively frangible crucible lining. Accordingly, it is anticipated that such a crucible may be suitably prepared prior to positioning in filling position within the apparatus of this invention and may be suitably moved from such filled position to another station at which the reducing process takes place. In case the crucible is delivered to an apparatus embodying this invention, with a removable mandrel, employed in lining preparation, still in place within said crucible, it is anticipated that suitable mandrel removing means and means for displacing any required portions of the filling equipment to insure such mandrel removal, may be added to the herein described structure without departing from the invention.

Referring now to Figure 1, a base structure 10 resting upon foundation line 11 supports a plurality of upright guide rods 12 on which a crucible cradle 13 is mounted for movement in a vertical plane, the crucible cradle as shown being in its lowermost position as occupied at the conclusion of the filling operation.

Supported by the rods 12, or by supplementary framework members, not shown herein for purposes of clarity, is a platform 14 adapted to support a vertically reciprocable filling and compacting structure later to be described. A conventional motor means 15 adapted to actuate said filling and compacting structure is mounted in any convenient manner adjacent said platform.

For the purpose of governing the movement of the crucible during loading and for preventing damage to the crucible lining, a pressure fluid system adapted to position the cradle elevator rod 16 is provided, preferably in a housing 17 disposed below foundation line 11. By means of conduits 18 and 19 a fluid, such as a suitable oil, may be supplied to and removed from the respective ends of an elongated stationary cylinder 20 within which is a piston, not shown, attached to the cradle elevator rod 16. Appropriate seals, fluid pumping means, and automatic pressure controlled valves, known to the art and forming no essential part of the invention, can be employed to effect the flow of such oil, to the end that the elevator rod 16 may be raised by pressure of oil supplied through conduit 19 and may be lowered as the oil is forced out through conduit 19, as when a predetermined compacting pressure, for example, is exerted upon the crucible.

Rigidly attached to the upper portion of elevator rod 16 is an enlarged cradle base support 21 adapted to contact loosely a resilient buffer 22 which in turn is rigidly affixed to crucible cradle 13 adjacent the bottom closure plate 23. A plurality of apertured webs 24, preferably are provided for mounting the cradle 13 and for permitting movement of the crucible cradle assembly in a vertical direction upon the guide rods 12. A crucible enclosing plate 28 having a suitable reentrant portion to position the crucible and adapted to be detachably clamped to the lower flange of a movable housing 30 through the intermediary of spacer 29 likewise is provided. A vertical plate 25 having an aperture 26 therein may be employed to space the bottom plate 23 and plates 28 and 29 at the desired vertical distance within the crucible

cradle 13. Moreover, during the employment of the improved apparatus any suitable clamping means not shown, which may be desired for detachably clamping the crucible and the several plates of the crucible cradle together as a unit, may be employed without departing from the invention. By means of this arrangement a prepared empty crucible, as in Figure 2, may be moved horizontally to the left as by means of rollers or dollies, not shown, moving on suitable rails and by use of remotely controlled guide means extending through the aperture 26 in plate 25 may be positioned within the cradle assembly as indicated in Figures 2 and 3. After being filled, such crucible preferably is moved to the right away from the cradle, the top layer of dolomite lining placed above the compacted materials, and a top metal cover placed upon the loaded crucible after which further operations, such as a reducing process, may be conducted upon the contents of the packaged container.

With the general arrangement of the improved combination of apparatus now in mind, reference is made to Figures 2 and 3 showing the crucible and the filling and compacing structure. As will be seen in Figure 2, housing 30 is provided with an annular plate 31 adjacent its lower edge and with a smaller annular plate 32 adjacent its upper edge. Secured to plate 32 is a vacuum header 33 having a conduit 34 adapted to be flexibly attached to a suitable vacuum source. Since housing 30 and the vacuum header are to partake of the movement imparted to the crucible cradle 13, it will be apparent that a flexible connection, such as a hose line, will customarily be employed to establish the vacuum within the thus described structure.

Positioned within the housing 30 and header 33 and guided by means of a pair of annular dust removing washers 35 and 36 is a hollow reciprocable filling tube having an inner wall 40 and an outer wall 41 spaced therefrom by an annular vent space 42 and adapted to partake of a reciprocating motion of predetermined range of travel as will later be described. Adjacent the lower end of said filling tube, as best shown in Figures 3 and 5, is a series of apertures 43 in the outer tube 41 establishing communication between the exterior of tube 41 and the vent space 42. Immediately below said apertures is a closure ring 44 completely bridging the space between the inner tube 40 and outer tube 41 and immediately adjacent the lower edge of said tubes is a similar ring 45 serving a similar purpose. Within the inner tube 40 at its lower end is a tamping or compacting spider member 46, best shown in Figure 5.

As shown in Figure 2, a suitable open ended crucible, which for example, may consist of an outer metal wall and bottom 50 and an inner lining 51 constructed of compacted finely divided dolomite, is employed, although the invention is in no way limited to a crucible consisting of these materials or to the configuration as shown. For example, the bottom of the crucible, rather than being flat as indicated for simplicity may well include a depression for holding the metal later to be derived from the treatment of the mixed materials charged therein. The crucible employed, however, when placed in the crucible cradle and raised into position where the spider 46 is disposed adjacent the crucible bottom, is ready to receive charge materials contained within the inner wall 40 of the filling tube. With the inner tube 40 containing a measured charge of solid materials, a portion of which is indicated at 52, upward motion of the filling tube with respect to the crucible will permit material to fall through the open spider 46. Downward motion of the tube thereupon compacts a part of the thus deposited material and as this action continues a compacted separate layer 53 of mixed materials is gradually built up within the lining 51. Moreover, as will later become apparent, as the filling and compacting action proceeds the entire crucible cradle is gradually retracted to a lower position until by the time the contents of the filling tube

have been exhausted the several parts have reached the relative positions shown in Figure 3. It will be noted that as the spider 46 moves with respect to the layer 53 of material any change in gaseous volume within the crucible lining is accommodated by passage of such gas along the surface of lining 51, through ports 43, and through vent space 42. This gas will carry fine dust which may tend to deposit within housing 30. Also the outer surface of wall 42 may tend to retain a film of such dust as it passes through header 33. Accordingly, it is contemplated that washers 35 and 36 in addition to their mechanical action of brushing against the outer surface of wall 42 will also serve as loose vacuum seals with the result that as suction is applied to conduit 34 a suitable small flow of air will be drawn into that conduit and thus serve to sweep away such dust from these surfaces.

Referring now to Figure 4, the upper portion of the reciprocable filling tube is shown as comprising a hopper member having a top plate 60 affixed to the outer wall 41 of the filling tube and with an inwardly extending baffle 61 overlying the upper edge of the spaced inner wall 40 of such tube.

Affixed to the top plate 60 is an upstanding filling attachment 62 including a removable cover plate 63 adapted to be removed during filling of the hopper and to be replaced at the conclusion of the filling operation. As will be apparent, a mixture of materials introduced in a given proportion into this attachment and thence through the hopper into the bottom of tube 40 will be distributed from that tube in the same proportion and will not segregate even if they have widely different specific gravities or particle size. Moreover, excess air displaced from the apparatus during filling or subsequent operation may be vented through a vacuum line 64 attached to the cover 63 and communicating with the interior of the filling attachment 62.

As shown in Figure 1, the filling tube, hopper and filling attachment may be mounted to reciprocate as a unit and are supported on diametrically opposite sides by similar crossheads 70 and 71 attached to the hopper sides and adapted to ride upon similar vertically disposed spaced stationary guide rods 72 and 73. Referring to Figure 4 it will be seen that the crosshead 70 has a pin 74 upon which a driving crank rod 75 is pivoted, the rod 75 in turn being pivoted at its lower end to a rocking lever 76 rigidly attached to rocker shaft 77. This rocker shaft which is mounted in substantially horizontal position upon platform 14 carries a second rigidly affixed rocking lever 78 which is pivotally mounted upon an eccentric sheave 79 adapted to be driven by an eccentric 80 affixed to a rotatable shaft 81 which is driven in turn by motor 15. A similar arrangement of a crank rod and a rocking lever arm attached to the rocker shaft preferably is employed to drive crosshead 71. As will be apparent to those skilled in the art, other mechanical drive arrangements for lifting and lowering the filling equipment through a desired range may be employed without departing from the invention.

As will thus be seen, rotation of shaft 81 which may be effected in any suitably controlled manner by remote control of motor 15 effects a vertically reciprocable movement of the filling and compacting elements of the invention, the range of movement of which is established by the eccentric drive, the length of the lever arms and the mounting of the crossheads, all as above described. The operation of motor 15 may be controlled by appropriate means, as for example by the use of microswitches, not shown, adapted to be operated by the movement of the crucible cradle 13. It is contemplated that motor 15 will be inoperative during the period when the crucible cradle is lifted to loading position; during the actual filling of the hopper and inner tube 40 and following the loading of a crucible. In the latter instance, it is undesirable to shake into the air any dust left

on the wall of tube 40 after the loading operation and it is within the purview of the invention to provide a suitable means, such as a pan or the like, not shown, adapted to rest under the spider 46 following a loading operation and to catch dust which otherwise might fall into the atmosphere from the wall of tube 40.

Having thus described the several elements of an apparatus for employing the invention, a cycle of operation thereof will be briefly outlined. With filling tube 40 empty and with an empty lined crucible available, the crucible first is positioned within the crucible cradle 13 occupying its lowermost position on the guide rods 12. Pressure fluid is supplied to cylinder 20 through pipe 19 and is vented from the cylinder through pipe 18 thus raising the cradle 13 to its uppermost position. Appropriate means are then used to clamp housing 30 to the crucible cradle assembly and the suction means connected to conduit 34 may be placed in operation. The filling attachment cover is removed and a measured amount of the mixed materials are deposited preferably by remote control means and in a uniformly mixed body into the hopper and thence into the bottom of tube 40. Cover plate 63 is then replaced and suction line 34 placed in operation.

With a predetermined relief pressure established on pressure fluid line 19, motor 15 may then be started and the above described filling and compacting as shown by Figures 2 and 3 will ensue. Each time the compacting pressure reaches the valve set for the relief pressure in line 19, a small amount of pressure fluid will be forced out of the bottom of cylinder 20 and an equivalent amount added to the top of that cylinder. As this occurs the crucible cradle assembly 13 is retracted downwardly stepwise and does not tend to rise during the next upward movement of the filling and compacting equipment. Accordingly, during the rise of this equipment another amount of properly mixed material falls from tube 40 through spider 46 and is tamped as the equipment makes its subsequent downward movement.

Finally when the crucible is filled, with preferably the contents of tube 40 being exhausted simultaneously, the connections between housing 30 and crucible cradle 13 are released and the loaded crucible is removed to another station for further processing.

Although this invention has been described with respect to particular embodiments thereof, it is not to be so limited as changes and modifications may be made therein which are within the full intended scope, as defined by the appended claims.

I claim:

1. A filling and compacting apparatus adapted to deposit a mixture of dust-forming solid materials in a container while confining the materials against escape into the surrounding atmosphere including, means supporting said container, a covered hopper receiving said mixture of materials, a movable filling tube connected at one end to said hopper and extending into said container at a second end, compacting means at the second end of said tube interiorly thereof, means for reciprocating said filling tube within said container and means for changing the relative positioning of said filling tube and container in dependence upon the pressure established upon the material by the compacting means as material is compacted in said container.

2. A filling and compacting apparatus adapted to deposit a mixture of dust-forming solid materials in a container while confining the materials against escape into the surrounding atmosphere including, means supporting said container, a covered hopper receiving said mixture of materials, a movable filling tube connected at one end to said hopper and extending into said container at a second end, a housing surrounding said tube adjacent the upper side of said container and adapted to receive dust particles deposited on the exterior of the tube during the filling operation, compacting means at the second end of

said tube interiorly thereof, means for reciprocating said filling tube within said container and means for changing the relative positioning of said filling tube and container in dependence upon the pressure established upon the material by the compacting means as material is compacted in said container.

3. Apparatus defined in claim 2, wherein said housing is mounted upon said container supporting means during the filling operation.

4. Apparatus defined in claim 2, wherein said housing is connected to a vacuum source during the filling operation.

5. A dust-tight filling and compacting apparatus adapted to deposit a mixture of solid materials in a container including, means supporting said container, a hopper receiving said mixture of materials, a closure for said hopper, a movable double walled filling tube having a space between said walls and connected at one end to said hopper and extending into said container at a second end, the inner portion of said tube being adapted to transfer materials to the container and the outer portions being adapted to transfer displaced air to said hopper, compacting means at the second end of said tube interiorly thereof, a housing disposed adjacent the container and through which said tube is adapted to reciprocate, apertures within said outer tube wall communicating the space within the container to the space between said tube walls, means for reciprocating said filling tube within said container and means for changing the relative positioning of said filling tube and container in dependence upon the pressure established upon the material by the compacting means as material is compacted in said container.

6. Apparatus defined in claim 5, wherein said housing includes an apertured plate member adapted to be detachably mounted upon said container supporting means.

7. Apparatus defined in claim 5, wherein said housing is provided with a seal having an air leak passage adjacent its contact with the exterior of the movable tube and is connected to a suction source thereby to remove dust particles deposited on the exterior of said tube.

8. Apparatus as defined in claim 5, wherein said compacting means comprises an open spider member.

9. In combination, a filling and compacting apparatus adapted to deposit a mixture of solid materials in a displaceable container including a hopper receiving said mixture of materials, a movable filling tube connected at one end to said hopper and extending into said container at a second end, compacting means at the second end of said tube interiorly thereof, container supporting means adapted initially to support the container floor adjacent said compacting means, means for retracting said container supporting means during the filling operation in dependence upon the pressure established upon the material by the compacting means, and means for reciprocating said filling tube within said container.

10. Apparatus as defined in claim 9 wherein said retracting means includes a fluid pressure system.

11. In combination, a filling and compacting apparatus adapted to deposit a mixture of solid materials in a displaceable container having a frangible lining including a hopper receiving said mixture of materials, a movable filling tube connected at one end to said hopper and extending into the space within said container lining at a second end, compacting means at the second end of said tube interiorly thereof, container supporting means adapted initially to support the container floor adjacent said compacting means, means for retracting said container supporting means during the filling operation in dependence upon the pressure established upon the material by the compacting means, and means for reciprocating said filling tube within said container.

12. Apparatus defined in claim 11, wherein the container supporting means includes a resilient shock ab-

sorbing structure supporting the bottom of said container.

13. A filling and compacting apparatus adapted to deposit a mixture of solid materials in a container including, means supporting said container, a hopper receiving said mixture of materials, a movable filling tube connected at one end to said hopper and extending into said container at a second end, compacting means at the second end of said tube interiorly thereof, a rotatable shaft, means driven by said shaft for effecting reciprocation of said tube and for exerting tamping pressure upon the material fed into said container and means for changing the relative positioning of said filling tube and container in dependence upon said tamping pressure as material is compacted in said container.

14. Apparatus of the class described including a resiliently mounted container supporting means, a container, a hopper for receiving material to be loaded into said container, a movable filling tube connected at one end to said hopper and extending into said container adjacent the bottom thereof at its second end, an apertured compacting means attached interiorly to said tube adjacent said second end, means for reciprocating said tube within said container thereby to permit material contained with said tube to flow through said compacting means when said tube is moved in one direction and to be compacted in the container by said compacting means when said tube is moved in the reverse direction and means for changing the relative positioning of said filling tube and container in dependence upon the pressure established upon the material by said compacting means as material is compacted in said container.

15. Apparatus as defined in claim 14 wherein said resiliently mounted supporting means includes a piston adapted to be displaced in a pressure fluid cylinder upon attainment of a predetermined compacting pressure by said reciprocating tube.

16. Apparatus as defined in claim 14 wherein said means for reciprocating said tube includes a motor driven rocker shaft adapted to impart to said tube a positive movement with a predetermined range of travel.

5
10

17. Filling and compacting apparatus of the class described including a container, an open ended hollow tube adapted to extend into said container and having an imperforate inner wall and an outer wall spaced therefrom to provide an air passage between said walls, a plurality of apertures in said outer wall adjacent one end thereof, an apertured compacting means joining said walls at said one end, means completely closing the air passage at said one end of the tube adjacent said compacting means, a double walled covered hopper attached to the other end of said tube and having an air space at the top thereof in communication with the air passage between the tube walls, whereby displaced air from the container entering the apertures of the tube outer wall may pass into the hopper above the contents held therein for discharge into the inner wall of said tube, means for reciprocating the hopper and tube in order to discharge the hopper contents from said one end of the tube and to compact the discharged material into said container, and means for retracting the container from the one end of said tube in dependence upon the pressure established upon the material by the compacting means.
